UNITED STATES PATENT OFFICE

105,406

DESIGN FOR A PIN BROOCH

Alfred Philippe, New York, N. Y., assignor to Tri-fari, Krussman & Fishel, Inc., a corporation of New York

Application February 13, 1937, Serial No. 67,652

Term of patent 3½ years

To whom it may concern:

Be it known that I, Alfred Philippe, a citizen of the United States, residing at New York, in the city, county, and State of New York, have invented a new, original, and ornamental Design for a Pin Brooch, of which the following is a specification, reference being had to the accompanying drawing, forming part thereof, wherein—

While I have shown my design embodied in a pin brooch, it is contemplated that the same may also be embodied in similar articles of jewelry without departing from the spirit of my invention.

I claim:

The ornamental design for a pin brooch, substantially as shown and described.

ALFRED PHILIPPE.
